ABSTRACT

1-Phthalazone derivatives or acid salts thereof which are represented by the formula:

wherein R is a hydrogen atom or an alkyl group; R₁ is a hydrogen atom, an alkyl, alkylsulfonyl, or arylsulfonyl group; or an aryl group which is represented by the formula:

wherein R₄ is hydrogen or halogen atom, an alkyl, or alkoxy group; R₅ is a hydrogen or halogen atom, an alkyl, alkoxy, or alkoxy carbonyl group;

R₂ is a hydrogen or halogen atom, an alkyl, or alkoxy group; R₃ is a hydrogen or halogen atom, an alkyl, alkoxy, alkoxy carbonyl, amino, or acylamino group; with the proviso that at least one of R, R₁, R₂ and R₃ is not hydrogen.

2 Claims, No Drawings

7-ALKOXYCARBONYL-4-HYDROXYMETHYL-1-PHTHALAZONE COMPOUNDS

The present invention relates to new phthalazone derivatives or pharmaceutically acceptable acid salts thereof for pharmaceutical use, and to a process for their manufacture.

One aspect of the invention consists of 1-phthalazone derivatives which are represented by the formula:

wherein R is a member selected from the group consisting of a hydrogen atom and an alkyl group, preferably a C₁-C₃ alkyl group; R₁ is a member selected from the group consisting of a hydrogen atom, an alkyl group, preferably a C₁-C₃ alkyl group, an alkylsulfonyl group, preferably an alkylsulfonyl group having a C₁-C₃ alkyl group, an arylsulfonyl group, preferably benzenesulfonyl and toluenesulfonyl groups and an aryl group which is represented by the formula:

wherein

R₄ is a member selected from the group consisting of a hydrogen atom, a halogen atom such as Cl, Br, I and F, preferably Cl and Br, an alkyl group, preferably a C₁-C₃ alkyl group, and an alkoxy group, preferably a C₁-C₃ alkoxy group; R₅ is a member selected from the group consisting of a hydrogen atom, a halogen atom such as Cl, Br, I and F, preferably Cl and Br, an alkyl group, preferably a C₁-C₃ alkyl group, an alkoxy group, preferably a C₁-C₃ alkoxy group, and an alkoxy carbonyl group, preferably an alkoxy carbonyl group having a C₁-C₃ alkoxy group;

R₂ is a member selected from the group consisting of a hydrogen atom, a halogen atom such as Cl, Br, I and F, preferably Cl and Br, an alkyl group, preferably a C₁-C₃ alkyl group, and an alkoxy group, preferably a C₁-C₃ alkoxy group; R₃ is a member selected from the group consisting of a hydrogen atom, a halogen atom such as Cl, Br, I and F, preferably Cl and Br, an alkyl group, preferably a C₁-C₃ alkyl group, an alkoxy group, preferably a C₁-C₃ alkoxy group, an alkoxy carbonyl group, preferably an alkoxy carbonyl group having a C₁-C₅ alkoxy group, an amino group, and an acylamino group, preferably an acylamino group having a C₁-C₃ acyl group with the proviso that at least one of R, R₁, R₂ and R₃ is not a hydrogen atom.

The above compounds can be manufactured by any of the following processes:

a. A compound of the formula:

wherein R₁, R₂ and R₃ have the same meanings as in formula (I) and Y is an alkoxy carbonyl group, preferably an alkoxy carbonyl group having a C₁-C₃ alkoxy group, or a halogenocarbonyl group having a halogen atom such as Cl or Br, is reacted with an alkali metal borohydride in the presence or absence of a metal halide.

b. A compound of the formula:

wherein R, R₂ and R₃ have the same meanings as in formula (I), is reacted with a hydrazine derivative of the formula:

wherein R₁ has the same meaning as in formula (I), excluding an aryl group.

c. A compound of the formula:

wherein R₁, R₂ and R₃ have the same meanings as in formula (I), and Z is an alkoxy carbonyl group, preferably an alkoxy carbonyl group having a C₁-C₃ alkoxy group, an aldehyde or acyl group, preferably a C₁-C₃ acyl group, is reacted with a Grignard compound of the formula,

wherein R has the same meaning as in formula (I), excluding a hydrogen atom, and X is a halogen atom such as Cl, Br or I.

The compounds of the present invention can be manufactured by any process described above. These compounds prepared are new. In the experimental atherosclerosis induced by cholesterol feeding, they showed

a profound effect for preventing atherosclerosis, inhibiting cholesterol deposition on arterial wall. They also prevented the enhancement of coagulability and thrombogenicity induced a one shot treatment of an animal with cholesterol or adrenaline. That is to say, they prevented the shortening of clotting times of the blood as well as the enhancement of adenosine diphosphate-induced platelets-aggregation in the animal. The compounds of this invention are useful for treatment of atherosclerotic and thrombotic diseases such as cerebral thrombosis, coronary thrombosis, peripheral thrombosis, cerebral atherosclerosis, coronary atherosclerosis, arteriosclerosis obliterans, thromboangiitis obliterans, thrombophlebitis, angiopathy of diabetes mellitus, and nephropathy of diabetes mellitus.

For example, there can be cited 7-chloro-4-ethoxycarbonyl-1-phthalazone, 7-bromo-4-methoxycarbonyl-1-phthalazone, 4-ethoxycarbonyl-7-methoxy-1-phthalazone, 4-ethoxycarbonyl-7-methoxy-2-phenyl-1-phthalazone, 5-acetylamo-4-ethoxycarbonyl-1-phthalazone, 8-acetylamo-4-ethoxycarbonyl-7-methoxy-1-phthalazone, 8-amino-7-chloro-4-ethoxycarbonyl-1-phthalazone, 6,7-dimethyl-4-ethoxycarbonyl-1-phthalazone, 4-methoxycarbonyl-2,6,7-trimethyl-1-phthalazone, 2-benzenesulfonyl-4-ethoxycarbonyl-7-methoxy-1-phthalazone, and 7-bromo-4-ethoxycarbonyl-2-(p-toluenesulfonyl)-1-phthalazone.

2. The compounds of formula (III) can be manufactured by the following reaction schemes.

(III)

(III)

The starting compounds used in this invention, which are expressed by formulae (II) and (III), can be manufactured by the analogous methods known in the art or the new methods described hereinafter.

1. The compounds of formula (II) can be manufactured by known methods [e.g., J. of Am. Chem. Soc., 68, 1316 (1946)] from naphthalene derivatives. Examples of the compounds include 4-ethoxycarbonyl-2-phenyl-1-phthalazone, 4-methoxycarbonyl-2-methyl-1-phthalazone, 4-ethoxycarbonyl-2-methanesulfonyl-1-phthalazone, 4-methoxycarbonyl-2-benzenesulfonyl-1-phthalazone, 4-ethoxycarbonyl-2-toluenesulfonyl-1-phthalazone, 4-ethoxycarbonyl-2-tolyl-1-phthalazone, 4-methoxycarbonyl-2-(p-methoxyphenyl)-1-phthalazone, 4-ethoxycarbonyl-2-(p-chlorophenyl)-1-phthalazone, 4-ethoxycarbonyl-2-(p-bromophenyl)-1-phthalazone, 4-ethoxycarbonyl-2-(p-ethoxycarbonyl-phenyl)-1-phthalazone, and 4-chlorocarbonyl-2-phenyl-1-phthalazone. Furthermore, 4-alkoxycarbonyl- or 4-chlorocarbonyl-1-phthalazone derivatives which have one or two substituents such as a chlorine atom, bromine atom, alkyl, alkoxy, amino, acetylamo, alkoxycarbonyl group in any of the C-5, C-6, C-7, and C-8 positions in the phthalazone nucleus, can also be used.

The authors of Ber. 40, 72 (1907) and Annual Report of Department of Pharmacy, Kanazawa University (Japan), Vol. 12, 1-6 (1961) claimed that they had obtained methylenephthalide or o- ω -hydroxyacetylbenzoic acid by hydrolysis of o- ω -bromoacetylbenzoic acid. We have found that the product is to be 4-oxo-3,4-dihydroisocoumarin. The compounds of formula (III), which have an alkyl substituent at the 3-position, can be manufactured by the alkylation of 4-oxo-3,4-dihydroisocoumarin. Examples of the compounds of formula (III) include 4-oxo-3,4-dihydroisocoumarin, 3-methyl-4-oxo-3,4-dihydroisocoumarin, 3,3-dimethyl-4-oxo-3,4-dihydroisocoumarin, and their derivatives which have one or two substituents such as a chlorine atom or a bromine atom, an alkyl, alkoxy, amino, acetylamo and alkoxycarbonyl group in any of the C-5, C-6, C-7, and C-8 positions in the dihydroisocoumarin nucleus.

In the embodiment of the process (a), the compound of (II) is reacted with an equimolar quantity or an excess, preferably between 1.5 and 10 moles per mole of compound (I), of an alkali metal borohydride such as sodium borohydride, potassium borohydride, or lithium borohydride. The reaction is preferably carried out

in the presence of metal halogenide, such as calcium chloride, magnesium bromide, lithium chloride, lithium bromide, or lithium iodide. Sodium trimethoxyborohydride can also be used. When the compound of (II) is 4-alkoxycarbonyl-1-phthalazone derivative, that is, Y in the formula (II) is an alkoxy carbonyl group, lower aliphatic alcohols such as methanol, ethanol or propanol can preferably be used as a solvent, and the reaction is preferably carried out at a temperature between 0° and 150°C., especially between 0°C. and 100°C. When the compound of (II) is the 4-chlorocarbonyl-1-phthalazone derivative, that is, Y in the formula (II) is a chlorocarbonyl group, a solvent such as dioxane, tetrahydrofuran or benzene can preferably be used, and the reaction is preferably carried out at a temperature between 0° and 100°C., especially between 0° and 50°C.

In the embodiment of process (b), a compound of formula (III) is reacted with an equimolar quantity or excess [preferably 1-10 moles per mole of the compound (III)] of a hydrazine derivative represented by formula (IV). Examples of the hydrazine derivative include hydrazine, methylhydrazine, methanesulfonylhydrazine, benzenesulfonylhydrazine, and p-toluenesulfonylhydrazine. Although the reaction can be carried out in the absence of solvent, it is carried out preferably in the presence of a solvent such as water, lower aliphatic alcohols, e.g. methanol, ethanol or propanol, and at a temperature between 0° and 150°C., especially between 50° and 100°C.

In the embodiment of process (c), the reaction can be carried out under the conditions conventional to Grignard reactions. Namely, the reaction is carried out in an anhydrous solvent such as ethyl ether, benzene or tetrahydrofuran. The reaction temperature between 0° and 100°C., especially 0° and 50°C. is preferably used. The Grignard compound of formula (V) is used in a quantity of 1-3 moles per mole of the compound of formula (VI).

Whatever process of manufacture is used, the product can be separated and purified by conventional methods to be described hereinafter.

The products of the present invention can form stable salts with a pharmaceutically acceptable inorganic acid such as sulfuric acid, hydrochloric acid, hydrobromic acid or hydroiodic acid, and an organic acid such as oxalic acid, maleic acid, citric acid, tartaric acid, nicotinic acid, salicylic acid and acetylsalicylic acid. These salts are water-soluble, and therefore they can be administered in the form of injection.

The invention is illustrated but not limited by the following Examples. All the UV spectra described in the Examples were measured in 95 percent ethanol.

EXAMPLE 1

To a stirred suspension of 2 g of 7-methoxy-4-ethoxycarbonyl-1-phthalazone 100 ml in methanol, 3 g of sodium borohydride were added portionwise. The reaction mixture was refluxed for 1.5 hours on a water bath. The excessive borohydride was destroyed by addition of acetone, and then the solvent was distilled off. The residue was dissolved in water, and the solution was adjusted to pH 6-7 with acetic acid and dried under reduced pressure. The residue was continuously extracted with chloroform using a Soxlet-apparatus. The chloroform was distilled off from the extract, and the residue so obtained was recrystallized from methanol to yield 1.5 g of 4-hydroxymethyl-7-methoxy-1-phthalazone melting at 229-230°C.

Analysis of elements:

	C	H	N
Calcd. (%) for C ₁₀ H ₁₀ O ₃ N ₂ :	58.25	4.89	13.58
Found (%):	58.42	4.82	13.60

UV spectrum: λ_{max} 222 m μ (ϵ =20,700), 280 m μ (ϵ =9,800), 286 m μ (ϵ =9,800), 302 m μ (ϵ =4,800), 314 m μ (ϵ =5,000) 327 m μ (ϵ =3,600)

EXAMPLE 2

To a solution of 3 g of 4-ethoxycarbonyl-2-phenyl-1-phthalazone 150 ml of methanol, 1.2 g of sodium borohydride and 100 mg of calcium chloride were added portionwise with stirring. The reaction mixture was refluxed for 1.5 hours on a water bath. After cooling, acetone was added to destroy the excessive borohydride, and then the solvent was distilled off. The residue was dissolved in water, and the solution was adjusted to pH 6-7. The solution was then extracted with chloroform. The chloroform extract was dried over MgSO₄ and distilled off. The residue was recrystallized from acetone to yield 2.5 g of 4-hydroxymethyl-2-phenyl-1-phthalazone melting at 160°-162°C.

Analysis of elements:

	C	H	N
Calcd. (%) for C ₁₅ H ₁₂ O ₂ N ₂ :	71.41	4.80	11.11
Found (%):	71.43	4.70	11.50

UV spectrum: λ_{max} 220 m μ (ϵ =35,200), 256 m μ (ϵ =6,700), 295 m μ (ϵ =7,800)

EXAMPLE 3

To a suspension of 2 g of 4,7-diethoxycarbonyl-1-phthalazone in 120 ml of ethanol heated at 70°-80°C. 1 g of sodium borohydride 100 mg and magnesium bromide were added portionwise with stirring. After the completion of the addition of borohydride, the reaction mixture was refluxed for 1.5 hours. The excessive borohydride was destroyed by the addition of acetone and the solvent was distilled off. The residue was dissolved in water. The pH of the solution was adjusted to 6-7 and the solution was dried under reduced pressure. The residue was extracted continuously with chloroform using a Soxlet-apparatus. The chloroform was distilled off from the extract, and the residue was recrystallized from methanol to yield 1.4 g of 7-ethoxycarbonyl-4-hydroxymethyl-1-phthalazone.

The product has the following structure.

Analysis of elements:

	C	H	N
Calcd. (%) for C ₁₂ H ₁₂ O ₄ N ₂ :	58.06	4.97	11.29
Found (%):	58.25	4.58	11.46

UV spectrum λ_{max} 215 m μ (ϵ =29,100), 230 m μ (ϵ =22,700), 252 m μ (ϵ =10,600), 262 m μ (ϵ =11,000), 305 m μ (ϵ =10,300), 317 m μ (ϵ =8,500)

EXAMPLES 4 to 14

In a manner similar to Examples 1-3, the following products of formula (I) were obtained from the compounds of formula (II') in a 60-90 percent yield, as shown in the following Table I.

EXAMPLE 25

A mixture of 3 g of 7-bromo-4-carboxy-2-methyl-1-phthalazone and 30 ml of thionyl chloride was refluxed gently at 70°-80°C. for 50 minutes on a water bath. The excess thionyl chloride was then distilled off, and the residue was dissolved in 30 ml of dioxane. To the dioxane solution 2 g of NaBH₄ was added portionwise at 0°-10°C. with stirring. The reaction mixture was further stirred for 1 hour, and then the solvent was distilled off. The residue was dissolved in water and the solution was extracted with chloroform. The chloroform was distilled off from the extract, and the residue was recrystallized from methanol-ethyl acetate to yield 1.2 g of 7-bromo-4-hydroxymethyl-2-methyl-1-phthalazone melting at 192°-193°C.

EXAMPLE 26

A solution of 1 g of 3-methyl-4-oxo-3,4-dihydroisocoumarin and 3 g hydrazine hydrate in 30 ml of ethanol was refluxed for 3 hours on a water bath. The solution was cooled to the room temperature, and then the precipitated crystals were filtered and recrystallized from methanol to yield 0.8 g of 4-(α -hydroxyethyl)-1-phthalazone melting at 158°-159°C.

In a manner similar to Example 26, 7-chloro-8-amino-4-oxo-3,4-dihydroisocoumarin was reacted with hydrazine to yield 7-chloro-8-amino-4-hydroxymethyl-1-phthalazone melting at 232°-234°C. (recryst. from methanol) in a yield of 67 percent.

UV spectrum: λ_{max} 220 m μ (24,800), 255 m μ (9,000), 270 m μ (9,000), 296 m μ (11,800)

EXAMPLE 31

A solution of a Grignard compound was prepared from 1 g of magnesium ribbon 5.86 g and methyl iodide 5.86 g in 100 ml of absolute ethyl ether by a conventional process. To the Grignard reagent described above a solution of 2.5 g of 4-ethoxycarbonyl-1-phthalazone in 50 ml of tetrahydrofuran was added dropwise at 10°-15°C. with stirring. The reaction mixture was refluxed for 2 hours, and then a 10 percent H₂SO₄ solution was added slowly. The precipitated crystals were filtered and recrystallized from ethanol to yield 2.0 g of 4-(α -hydroxyisopropyl)-1-phthalazone melting at 212°-213°C. The compound has the following structure.

Analysis of elements:

	C	H	N
Calcd. (%) for C ₁₁ H ₁₂ O ₂ N ₂ :	64.69	5.92	13.72

EXAMPLE 39

The compounds of the present invention showed a preventive effect for the enhancement of coagulability and thrombogenicity by a one shot treatment of an animal with cholesterol or adrenaline, as shown below.

After oral administration of 10 mg/kg of the compound of the present invention to a rabbit, the intensity of platelet aggregation induced by adenosine diphosphate was measured by the Born's method (Born, J. Physiol. 162, 67 (1962), see also O'Brien, J. Clin. Path. 15, 452 (1962), Lancet, 1, 779 (1968)).

A rabbit was injected with adrenaline (1 µg/kg) 3 hours after oral administration of the sample. Five minutes after the injection, 4.5 ml of blood were taken from the carotid artery and then diluted with 0.5 ml of a 3.8 percent solution of sodium citrate. After centrifugation of the blood at 1000 g. for 30 minutes, 0.9 ml aliquots were taken from the supernatant. To the aliquots 0.1 ml of 3×10^{-5} molar and 10^{-4} molar solutions of adenosine diphosphate were added. Therefore the molar concentrations of ADP in the serum were 3×10^{-6} and 10^{-5} respectively. The intensity of platelet aggregation was measured using a platelet aggregation meter (Model 169, Evans Elect. Ltd. England). Intensities of the ADP-induced platelet aggregation were shown as percentage of the pre-injection value. As shown in the following Table IV, the compounds of this invention showed lower values of the ADP-induced platelet aggregation, thus preventing enhancement of coagulability and thrombogenicity. In the following Table, LD₅₀ values of the compounds of the invention are also shown.

Table IV

Com- ound	The enhancement of intensity of ADP-induced platelet aggregation		LD ₅₀ (mg/kg)
	3×10^{-6} M	10^{-5} M	
saline (control)	121.8±7.8%	115.1±4.9%	
dibenzyline (control)	101.7±8.7%	106.7±7.3%	
pyridinolcarbamate (control)	109.0±5.9%	100.8±6.5%	
aspirin (control)	106.0±3.0%	111.5±2.6%	
4-hydroxymethyl-2- phenyl-1-phthalazone	79.3±4.3%	77.0±3.3%	4,000
4-(α -hydroxyethyl)-1- phthalazone	82.0±5.2%	79.3±3.1%	3,500
4-(α -hydroxyisopropyl)- 1-phthalazone	78.5±2.8%	76.9±4.2%	3,500
4-hydroxymethyl-2-(p-

5	Com- ound	The enhancement of intensity of ADP-induced platelet aggregation		LD ₅₀ (mg/kg)
		3×10^{-6} M	10^{-5} M	
	-toluenesulfonyl)-1- phthalazone	84.1±4.2%	82.5±3.6%	3,000
10	4-hydroxymethyl-7- methoxy-1-phthalazone	83.5±3.5%	81.0±3.6%	3,500
	4-hydroxymethyl-2- methanesulfonyl-1- phthalazone	78.4±5.1%	75.4±3.9%	3,000

EXAMPLE 40

Effect of the compounds for the prevention of experimental atherosclerosis

The compounds of the present invention showed a profound effect for the prevention of atherosclerosis, inhibiting cholesterol deposition on arterial walls in the experimental atherosclerosis.

25 Ninetyfive healthy male rabbits were each fed with 150 g per day of pellets containing 1 percent cholesterol for 15 weeks. Thereafter 5 rabbits above mentioned were sacrificed. The remaining 90 rabbits were divided into six groups. While all of the groups were fed with standardized food, the five groups were administered each with 10 mg per kg of the compound of the present invention, the remaining one group with placebo consisting potato starch. After 6, 10 and 20 weeks, and each five rabbits of the six groups were sacrificed, and the total contents of cholesterol in the arterial walls were estimated by gas chromatography. The results are shown below in the Table V.

- 30 1. The total-cholesterol content at the end of the first 15 weeks was 48.09 ± 11.6 µg/mg dry weight.
- 35 2. The total-cholesterol contents of the six groups were indicated in the following table. The contents were shown in µg unit per one mg of the dried arterial wall. The value in the table is the average of five rabbits.

Table V

50	Groups administered with	Period (week)	Cholesterol content (µg)	
			placebo	4-hydroxymethyl-2-phenyl- 1-phthalazone
		6	30.4 ± 3.2	29.4 ± 2.2
		10	32.9 ± 2.8	
		20	26.0 ± 6.4	
55	4-(α -hydroxyethyl)-1- phthalazone	6	12.6 ± 2.5	12.4 ± 2.1
		10	5.3 ± 3.2	7.3 ± 2.6
		20	30.1 ± 4.2	28.9 ± 4.1
60	4-(α -hydroxyisopropyl)- 1-phthalazone	6	14.6 ± 3.5	12.4 ± 2.1
		10	7.6 ± 2.2	7.3 ± 2.6
		20	29.7 ± 4.6	28.9 ± 4.1
65	4-hydroxymethyl-2-(p- toluenesulfonyl)-1- phthalazone	6	13.9 ± 3.8	14.6 ± 3.5
		10	7.4 ± 3.6	7.6 ± 2.2
		20	28.7 ± 5.1	29.7 ± 4.6
	4-hydroxymethyl-7-methoxy- 1-phthalazone	6	13.6 ± 3.1	13.9 ± 3.8
		10	8.2 ± 2.4	7.4 ± 3.6

What is claimed is:

1. A compound of the following formula:

wherein R₃ is alkoxy carbonyl having C₁-C₅ alkoxy and the water-soluble pharmaceutically acceptable acid salts thereof.

2. 7-Ethoxycarbonyl-4-hydroxymethyl-1-phthalazone or a water-soluble, pharmaceutically acceptable acid salt thereof.
